UNITED STATES PATENT OFFICE.

CHARLES JEROME ABBEY, OF SKOWHEGAN, MAINE.

BLOWER FOR SAWS.

Application filed May 5, 1926. Serial No. 106,911.

This invention relates to blowers for cutting tools such as saws.

The principal object of the present invention is the provision of a blowing device capable of being attached to a saw for removing the sawdust from the lines or marks to be worked to without requiring the workman to change from a chosen or necessary position in operating the saw and which can be operated by the thumb of the hand in a manner which will not affect the gripping of the saw handle required for the skillful manipulation of the saw in the cutting operation, therefore enabling the workman to perform work easier in much less time and more efficiently.

Another object of the invention is the production of a blowing device capable of being removably attached to a saw in a convenient place on the handle, having features of adjustment by which the puff or blast of air created by the manipulation of the device may be readily changed so as to suit the convenience of the workmen; the device having structural features which permits the same to be easily transferred from one saw to another, and capable of being easily reassembled for right hand use or left hand use.

With the foregoing, other objects of the invention will appear from the embodiment of the invention which by way of example is described in the following specification and illustrated in the accompanying drawings, in which—

Figure 1 is a perspective view showing the device of the present invention in place on the handle of a saw, part of which is broken off, and the application of the device being for right hand use.

Fig. 2 is a sectional view through the device itself.

Fig. 3 is a sectional view taken on the line 3—3 of Fig. 2 and looking in the direction indicated by the arrows.

Fig. 4 is a sectional view taken on the line 4—4 of Fig. 2 and looking in the direction indicated by the arrows.

In the illustrated embodiment of the invention there is shown a hand saw 10 having a handle 11 to which the blowing device of the present invention is attached for right hand use by a workman for removing the sawdust from the lines or marks to be worked to so that cutting operations may be carried out easily and accurately without re-

quiring cessation of the reciprocation of the saw, and without requiring the workman to change from a chosen or necessary position.

The device, generally stated, consists of an air cylinder or tube 12, attaching means 13 for supporting and for adjustably and detachably connecting the cylinder 12 to the handle 11, means 14 for effecting and for maintaining the adjustment of the cylinder 12 with respect to the attaching means 13, and means 15 which operates in conjunction with the cylinder 12 for creating a puff or blast of air.

More specifically stated, the invention consists of the structural features and operates in a manner presently to be described. The attaching means 13 consists of a plate 16 having an angularly disposed member 17 having a slot 18 therein which opens out through its side edge as at 19, for the accommodation of a clamping element 20 which is secured to the top of the handle 11. The clamping element consists of a screw 21 which extends upwardly through the slot 18, and a nut 22 on the screw 21 for setting up a clamping action against portions of the member 17. The arrangement is such that the plate 16 is detachable and is also capable of being adjusted to any desired position. The means 14 for effecting the adjustable connection of the cylinder 12 to the attaching means 13 and for maintaining the cylinder 12 in different adjusted positions, in the present instance consists of an arm 23 carried by the cylinder, an element 24 adapted to be received in an opening in the end of the arm 23, and which element is also adapted to be screwed into a threaded hole in the plate 16 as at 25, to thus permit the cylinder 12 to be swung from one position to another. The cylinder 12 is held in its different positions of adjustment by virtue of the series of holes 26 in the plate 16 which are arranged in an arc of a circle described from the point of pivotal connection of the arm, and a headed element 27 carried by the arm which is adapted to enter any one of the holes 26 by flexing the arms 23 and then swinging the cylinder 12 and its arm 23 to a position in which the head of the element 27 will register with one of the holes 26.

The means 15 which operates in conjunction with the cylinder 12 for creating a puff or blast of air, in the present instance includes a head member 28 secured in one

end of the cylinder 12, the said member having a passage 29 therein. The head member 28 is provided with a nipple 30 which accommodates a nozzle 31 whose passage 32 is in line with the passage 29. A head member 33 is arranged in the opposite end of the cylinder 12 and is detachably secured therein by virtue of screws 34. The head member 33 is provided with a central bore 35 which extends through a gland 36 formed on the head member 33. A plunger 37 of any suitable construction is arranged for movement in the cylinder 12. The plunger in the present instance consists of a part 38 and a part 39 between which is arranged a gasket or leather disk 40. A rod 41 is connected to the parts 38 and 39 so that the plunger will be arranged at one end of the rod 41, and its opposite end extends through the bore 35 in the head member 33. The free end of the rod 41 is provided with an eye 42 to which is connected a flexible element 43, the said flexible element being also connected to a lever 44 as at 45. The pivot 46 of the lever includes a member 47 threaded on a stud 48 carried by the plate 16; the lever having an eye 49 which encircles the stud 48. The lever is of irregular shape and is provided with a thumb piece 50 for conveniently manipulating the same. The flexible element 43 is passed over a small grooved roller 51 mounted on an arbor 52 detachably carried by the plate 16. Two of these arbors 52 are provided and each serves as a spacer 53 for securing a cover 53 in place, the same being held in place by screws 54 which are screwed into bores respectively in the ends of the arbors 52. By providing two arbors 52 it is possible to reverse the arrangement 40 of the parts so that the device will be adapted for left hand use. In this connection it is also to be noted that there are two sets of holes 26 and an additional threaded hole 55 arranged with respect thereto for swingingly mounting the cylinder 12.

The lever 44, flexible element 43 and rod 41 serve as a means for retracting the plunger 37 for the purpose of taking air into the cylinder between the plunger and the head member 28. In order to eject the air taken into the cylinder rapidly so as to create a puff or blast of air there is provided in conjunction with the nozzle 31, a coil spring 56 which is arranged between the head member 33 and the part 39 of the plunger, as shown most clearly in Fig. 2. The coil spring 56 functions after the plunger 37 has been retracted in the manipulation of the thumb piece 50, immediately upon the release of the thumb piece to force the air out of the cylinder through the nozzle 31 in the form of a puff or blast of air.

From the foregoing it will be apparent that there has been described a device which will be thoroughly efficient and effectual for

blowing sawdust from lines or marks worked to by a workman by the mere manipulation of the thumb piece 50 with the thumb of the hand used for carrying out the cutting operation without requiring cessation of the reciprocation of the saw and without requiring the workman to change a chosen position which would interfere with the proper execution of the work in hand; that the blower has features of adjustment by virtue of which the blast of air may be directed in any desired direction and in which the air cylinder will be disposed so as not to interfere with the vision of the workman; and that the device has features of construction permitting the parts to be reassembled so that it may be used in connection with a saw for left hand use, and which may be readily detached so that the saw may be used without the device.

It is to be understood that the invention is not restricted to the precise arrangement of parts shown and described, as details of construction may be modified and rearranged without departing from the spirit of the invention, the scope of which is limited only by the terms of the appended claims.

I claim:

1. A sawdust blower for a hand saw comprising an air cylinder, attaching means for effecting the attachment of the cylinder on the handle of the saw, a plunger arranged for movement in the cylinder, a nozzle at one end of the cylinder, said cylinder being swingingly mounted by a means connected to a part of said attaching means, means for releasably maintaining the cylinder in different adjusted positions obtained by virtue of swinging movement, means for moving the plunger in one direction for the purpose of taking air into the cylinder between the plunger and the nozzle, and means which actuates the plunger to eject the air from the cylinder through the nozzle in the form of a puff or blast.

2. A sawdust blower for a hand saw comprising an air cylinder, attaching means for detachably securing the air cylinder on the handle of the saw, a plunger arranged for movement in the cylinder, a nozzle at one end of the cylinder, plunger retracting means operable for retracting the plunger for the purpose of taking air into the cylinder between the plunger and the nozzle, and means which operates the plunger when the retracting means is released for ejecting the air from the cylinder through the nozzle in the form of a puff or blast.

3. A sawdust blower for a hand saw comprising an air cylinder having a nozzle at one end, attaching means for detachably and adjustably securing the air cylinder on a part of the saw, said attaching means including a plate; an arm on said cylinder pivotally connected to said plate, means on the

plate which coacts with means on the arm for releasably maintaining the cylinder in different adjusted positions with respect to the plate, a plunger movable in said cylinder, retracting means operable irrespective of the position of the cylinder for retracting the plunger for the purpose of taking air into the cylinder between the plunger and the nozzle, and means which actuates the plunger to eject the air from the cylinder through the nozzle in the form of a puff or blast.

4. A sawdust blower for a hand saw comprising an air cylinder having a nozzle, means for adjustably supporting the air cylinder from the handle of the saw, a plunger arranged for movement in the cylinder, retracting means operable irrespective of the adjustment of the cylinder for retracting the plunger for the purpose of taking air into the cylinder between the plunger and the nozzle, and means which operates the plunger when the retracting means is released to eject the air from the cylinder through the nozzle in the form of a puff.

5. In a device of the class described, attaching means, an air cylinder adjustably carried by the attaching means, a plunger arranged for movement in said cylinder, a nozzle at one end of said cylinder, a lever, a flexible element connected between the lever and the plunger, a roller over which the flexible element passes, the plunger being moved in one direction when the lever is manipulated, thus admitting air into the cylinder between the plunger and the nozzle, and means acting on the plunger which functions to quickly move the plunger toward the nozzle upon the release of the lever for ejecting the air from the cylinder through the nozzle in the form of a puff.

6. In a device of the class described, means for creating a puff of air including an air cylinder mounted for pivotal movement on a plate, and means connected to the cylinder which coacts with means on the plate for releasably maintaining the air cylinder in different adjusted positions.

CHARLES JEROME ABBEY.
